(76) Inventor: **James Stimpson**

James Thompson, Baltimore etc.

Letters Patent.

The Schedule referred to in these Letters Patent making part of the same, containing a description in the words of the said James Thompson himself of his improvement in the construction of wheels for rail road carriages.

To all whom these presents shall come; Be it known that I, James Thompson, of the City & County of Baltimore, State of Maryland have invented a new & useful improvement in the construction or form of Road or Rail wheels, intended for the use of Rail Road carriages of every description whatever, and that the following is a full and exact description of the construction of the said wheels, invented or improved by me, viz. I propose to add to the common wheel as now used a ring rim, or fellow (or whatever it may be properly called) to the inside or inner periphery of the wheel, if the same link up with the rim or periphery of the wheel at the outer edge where it joins to said wheel, more or less, extending in from the rim or inner periphery of the wheel towards the nave, one to three inches more or less, as may be desired; which ring, rim, or fellow, should run on the outer edge, and opposite side of the wheel to that of the flange which flange guides the wheels upon the track rails, and from its necessary thickness & width, makes that edge of the rim or periphery of the wheel, much the strongest, although much less exposed to blow out or being broken than the outer edge of the wheel, which runs upon the rail as the last mentioned edge of the wheel, is liable to pass over all the obstructions or impediments that may be accidentally or designedly left upon the rails; this inner ring rim, fellow or flange, should be just flush with the outer edge or side of the rim of the wheel, its whole thickness extending in with its inside joinings, so as to make it solid to with its rim.

cast solid at the same time with the wheel. The whole object of the ring or felloe being to obtain the greatest strength possible with the least weight of metal, and I have no doubt fifteen pounds of iron thus disposed will afford as much protection to the wheel against breaking from severe percussions upon the road, as one hundred pounds equally distributed throughout the whole of the rim. What I claim as my invention or improvement, is the application of the rim ring or felloe inside the tread, or rim, or inner periphery of the wheel as opposite to the flange set forth in the above specification.

Harris Thompson
Letters Patent

The Schedule referred to in these Letters Patent and making part of the same containing a description in the words of the said Charles Thompson himself of his improvement in the mode of turning short curves on Rail Roads for which Letters Patent were granted dated the twenty third day of August 1831, which Letters Patent being hereby cancelled on account of a defective Specification.

1. *Original* *copy* *dated* *Aug 23 1831*
To all whom these presents shall come. Be it known that I, Charles Thompson of the city and County of Baltimore and State of Maryland have invented a new and useful improvement in the mode of turning short curves upon rail roads with railroad carriages particularly those round the corners of streets whenever the need that the following is a full and exact description of said invention or improvement as invented or improved by me. Fig. 1 is a view of the common peripheries of the flanchers of the flanchers of the wheels for the aforesaid purpose in the following manner. Let a flat rail upon which however may be secured if preferred at the commencement of the curve and in a position to be vertical to under the flanchers of the wheels upon the outer track of the circle so that no other part of the wheel which runs upon the outer side of the track will touch or bear upon the rails but the peripheries of the flanchers they bearing the whole weight of the load and carrying while the opposite wheels which run upon the inner track of the circle are to be run and bear upon their tracks in the usual way and their flanchers run freely in a groove or channel, which runs are ordinarily about three inches in diameter less than the peripheries of the flanchers. When the bearing surfaces of the wheels which are in contact with the rail while the turning the curve ^{to be} connected by straight lines from every point there would thus be formed the junctions of two cones if there be four wheels and two axles to the carriage or if but one axle and two wheels then but one cone, which junctions, or the wheels representing them, optically will of the wheels ~~are~~ the top, inches in diameter and are coupled about three, forty inches apart turn a curve of about sixty feet of the inner track rail. The difference in diameter between the flanchers and heads before stated, the track of the road width and the wheels coupled

coupling as stated would turn a curve of a somewhat smaller radius if the axles were not confined to the carriage in a parallel position with each other but this being generally deemed necessary the wheels run upon lines of tangents and then upon the inner track being as wide apart in the coupling as the outer ones keep constantly inclining the carriage outwards and thus cause the carriage to tend to run upon a larger circle than the difference in diameter of the tracks and flanchers would otherwise give but the depth of the flanchers and the couplings may be so varied as to turn any other radius of a circle desired. What I claim in my invention or improvement is the application of the flanchers of the wheel on one side of rail road carriages and of the tracks of the wheels on the other side, to turn curves upon rail ways particularly such as turning the corners of the streets, wharves &c. in cities and elsewhere operating upon the principle herein set forth.
